Attorneys.

UNITED STATES PATENT OFFICE

AUGUST LEANDER NILSSON, OF SODERTALJE, SWEDEN

CARBURETOR

Application filed April 7, 1928, Serial No. 268,256, and in Germany April 14, 1927.

In order to enable starting of an internal combustion motor when cold, an arrangement is required in the carburetor facilitating such adjustment of the latter that the fuel mixture will be abnormally rich in fuel at the start. According as the commercial motor fuel is rendered qualitatively inferior in the course of time by a decrease of the amount of lighter hydrocarbons contained therein, such an arrangement in the carburetor has become of an ever increasing importance in the running of motor vehicles.

The devices hitherto used for this purpose are substantially based on the principle of providing, by throttling of the air in the air-intake of the carburetor, first, a reduction of the entering quantity of air and, second, an increase of the vacuum causing the outflow of the fuel from the fuel container, the amount of fuel being thus increased simultaneously with a decrease of the amount of air.

In such arrangements, however, the risk is incurred that too great an amount of ungassed fuel enters the motor on an increase of the number of revolutions of the motor, after the start has been effected.

The present invention is based on the principle that an additional quantity of fuel is introduced at the start, without any alteration then taking place either with respect to the quantity of air or the amount of the escaping fuel, when the vacuum in the air-intake is subsequently increased.

The invention is principally characterized by the fact that there is arranged between the air-intake on the one hand and the fuel container of the carburetor on the other hand, a connection such that a quantity of fuel present therein by reason of the hydraulic pressure from the container is entrained on account of the air flowing through the air-intake when the said connection is opened.

An embodiment of the invention is disclosed in the accompanying drawing showing by way of diagrammatic representation a vertical section through a carburetor provided with means according to the invention.

1 designates the carburetor casing, 2 the

air-intake, 3 the fuel container, 4 the main calibrated opening, 5 a channel leading to the atomizer 6, 7 the calibrated opening for idle running, 8 the channel for idle running, which latter channel opens in the wall of the carburetor casing 1 at the throttling member 9. 10 denotes a connecting passage between 5 and 8, and 11 a slide having a passage 12 by means of which the communication between the channels 5 and 8 may be opened or closed.

At the start of a cold motor, the slide 11 is turned so that the connection between channels 5 and 8 is opened. In addition to the fuel then flowing from the calibrated opening 7 for idle running and out through the channel 8, the whole of the fuel quantity present in the channel system outside the main nozzle 4 will then also be sucked through the channels 10 and 12 into the channel 8 for idle running and, further, out through the port 14 at the throttling member 9, where the fuel is atomized and mixed with air.

The fuel mixture thus obtained is, to begin with, very rich in fuel, but is automatically rendered poorer as soon as all fuel in the said channel system has been sucked off. The mixture, however, continues to be richer than that used in normal idle running, inasmuch as all fuel escaping through the main calibrated opening 4 by reason of the hydraulic pressure is sucked into the channel 8 for idle running, together with air from the air opening 13. It is conditional, however, for the operation of such an arrangement, that the main calibrated opening 4 is situated below the fuel level, and that a certain amount of fuel passing the main calibrated opening 4 is contained in the channel system through which the slide 11 is connected with the channel 8 for idle running.

What I claim is:—

1. In a carburetor, the combination of a fuel container, an atomizer, an idling outlet, a conduit connecting said fuel container to said atomizer, a second conduit connecting said fuel container to said idling outlet, a calibrated opening between said container and said conduits, an air inlet between said

calibrated opening and said idling outlet, a second calibrated opening between said air inlet and said first named calibrated opening, a third conduit affording communication between the conduit leading to the atomizer and that portion of the conduit leading to the idling outlet, which lies between the second named calibrated opening and the idling outlet and a valve in said third conduit for closing the same after motor starting has been effected.

2. The combination with a carburetor having a fuel container, an idling outlet, an idling conduit between said outlet and said container, a calibrated orifice in said conduit, an atomizer, and a fuel conduit between said container and atomizer, of a conduit extending between said idling conduit at a point above said calibrated orifice and said fuel conduit at a point below the normal fuel level in said container, and a valve in said last conduit.

3. The combination with a carburetor having a fuel container, a calibrated outlet therefor, an idling outlet connected to said outlet by an idling conduit, an air inlet and a calibrated orifice in said idling conduit, an atomizer, and a fuel conduit connecting said orifice with said atomizer, of a conduit connecting said idling and fuel conduits, said connecting conduit opening into said idling conduit above said calibrated orifice and opening into said fuel conduit below the normal fuel level in said container, and a valve in said last conduit.

In testimony whereof I affix my signature.

AUGUST LEANDER NILSSON.
